UNITED STATES PATENT OFFICE.

SWIBERT ZIMMERMANN, OF NEW YORK, N. Y.

FOLDING BED.

SPECIFICATION forming part of Letters Patent No. 498,602, dated May 30, 1893.

Application filed February 2, 1893. Serial No. 460,756. (No model.)

To all whom it may concern:

Be it known that I, SWIBERT ZIMMERMANN, of New York city, New York, have invented an Improved Folding Bed, of which the following is a specification.

This invention relates to a folding bed which when closed constitutes a table and which is provided with a hinged extensible foot piece, that permits the bed to be made longer than the length of the table.

In the accompanying drawings: Figure 1 is a side elevation of the bed showing it open; Fig. 2 a longitudinal section showing it closed, and Fig. 3 a top view of the foot piece c, showing it lowered.

The letters a, represent the side pieces of the bed, supported upon feet as usual and connected at one end by the head piece a'. To this head piece there is hinged a plate b, that extends over the entire bed and which when let down constitutes a table. The foot piece c, of the bed is made of peculiar construction. It is hinged to a transverse rail c', of the bed bottom and is provided on its upper side with a pair of rails c², folding between side pieces a, and with a plate c³, which connects the rails c², and is set back from the upper edge of the end piece c. To this upper edge there is pivoted a pair of legs c⁴. When the foot piece is folded upward (Fig. 2) the plate c³, extends parallel to the bed bottom and constitutes a play table for the child. In this position the foot board is locked by a bolt c⁵, and the upper edge of the foot board constitutes a rest or support for the table b. When the foot piece is folded downward (Fig. 1), the foot piece itself constitutes an extension of the bed bottom thus enlarging the size of the bed. The side rails c², constitute an

extension of the side pieces a, and the plate c³, constitutes a foot rest. In this position the foot piece is supported by the legs c⁴. The table b, is secured in its upright position, by means of the bolt b', engaging eye b², of the head piece a' (Fig. 2). To the lower face of the table there is pivoted a frame f, carrying a mosquito net f³, and operated by string f⁴.

In order to support the mattress A, I employ in lieu of the usual bed bottom, a set of hooks i, projecting beneath the lower edge of side pieces a. In this way the bed is deepened, which is of importance, as its height is necessarily limited to the ordinary height of a table.

When the entire device is folded, it constitutes as already stated, a complete table. When it is to be used as a bed, the plate b, is raised and locked in position by the bolt b'. The foot piece may however, remain folded upward as in Fig. 2, when the device will constitute a child's crib. To form a bed for adults, the foot piece c, is swung down (Fig. 1), when the bed will be lengthened, to an extent equal, substantially, to the height of the foot piece.

What I claim is—

The combination of a bed having a head piece with a table plate hinged thereto and with a folding foot piece provided with pivoted legs and a top plate c³ which is secured to the foot piece below the lower edge of the same and projects beneath the table plate when the bed is closed, substantially as specified.

SWIBERT ZIMMERMANN.
